(57) **CLAIM**

The ornamental design for a microscope, as shown and described.

DESCRIPTION

FIG. 1 is a frontal perspective view of the microscope of the present invention;

FIG. 2 is a left side elevational view of the microscope of the present invention;

FIG. 3 is front elevational view of the microscope of the present invention;

FIG. 4 is a right side elevational view of the microscope of the present invention;

FIG. 5 is a rear elevational view of the microscope of the present invention;

FIG. 6 is a top view of the microscope of the present invention; and,

FIG. 7 is a bottom view of the microscope of the present invention.
